(57) **CLAIM**

The ornamental design of a hunter's seat with webbed frame and uneven articulated legs, as shown and described.

DESCRIPTION

FIG. 1 is a perspective view of a hunter's seat with webbed frame and uneven articulated legs, according to the new design;

FIG. 2 is a top plan view thereof,

FIG. 3 is a bottom plan view thereof, showing a stowed arrangement of the carrying strap thereof;

FIG. 4 is a side elevation, from the left side in FIG. 1;

FIG. 5 is a side elevation, from the right side in FIG. 1;

FIG. 6 is a front elevation view, from the right in FIG. 4;

FIG. 7 is a rear elevation view;

FIG. 8 is a side elevation as in FIG. 4, as the design of the invention appears on a sloped surface, the surface being shown in broken lines and forming no part of the invention; FIG. 9 is a perspective view of the design as configured for carrying; and,

FIG. 10 is a bottom plan view thereof, showing folded legs.
